UNITED STATES PATENT OFFICE.

ROBERT BENEDICT GOLDSCHMIDT, OF PARIS, FRANCE.

WIRELESS SELECTION SYSTEM.

Application filed June 25, 1920. Serial No. 391,789.

(GRANTED UNDER THE PROVISIONS OF THE ACT OF MARCH 3, 1921, 41 STAT L., 1813.)

To all whom it may concern:

Be it known that I, ROBERT BENEDICT GOLDSCHMIDT, a subject of the King of Belgium, residing at 350 Rue Saint Honore, 5 Paris, France, have invented certain new and useful Improvements in Wireless Selection Systems (for which I have filed applications for patents in Belgium December 29, 1913, and addition on May 2, 1914; 10 Great Britain, June 12, 1914, and addition on June 23, 1914; Germany, May 25, 1914; and France January 20, 1920), of which the following is a specification.

Communication by electromagnetic waves 15 is frequently disturbed at a receiving station either by extraneous signals or by atmospheric discharges collected by the antenna together with the waves intended to be received.

20 Electrical systems of selection, dependent on syntony, are very often insufficient to eliminate extraneous signals, if powerful or much damped or of a wave length approximating to that of the wave to be received, 25 and are nearly ineffective against severe atmospheric disturbances.

The purpose of the apparatus forming the subject of the present application is to effect 30 a mechanical selection of the signals collected by the receiving antenna in order to eliminate parasitic signals.

This mechanical selection is applicable to 35 all receiving systems, whatever electrical method of selection, which is generally based on syntony, be employed.

The principle of the system is as follows:—

There being a receiver and a receiving 40 antenna, a commutator is inserted in the antenna circuit by which the antenna can be connected to or disconnected from the receiver with a frequency equal to the frequency of the trains of waves it is desired to receive, the time of opening and closing 45 of the circuit being moreover regulable.

In other words, the receiving apparatus is only connected with the antenna during the time of reception of each train of waves of the radiation to be recorded, and no other 50 can influence it.

Supposing that the radiation to be received gives a musical note of a frequency of 500, that is to say there are 500 trains of waves per second, the antenna will be con-

nected to the receiver 500 times a second, 55 connection being made before the passage of each train of waves and broken after it.

It will be readily understood that extraneous radiations or atmospheric perturbations will only be able to operate on the 60 receiver if the trains of waves of which they consist are collected exactly at the instant when the antenna and receiver are joined; which can only happen by accident and cannot disturb the main radiation which is 65 to be received.

The two principal conditions which should be realized in such a system are:—

(1) Synchronism between the interruptions of the receiving commutator and the 70 succession of trains of waves of the radiation to be received, that is to say $f_2=f_1$.

(2) Agreement of phase between the closing of the circuit between antenna and receiver by the commutator and the passage 75 of each train of waves.

Synchronism can be secured by means of various mechanical, electrical, magnetic, electromagnetic or other regulators or commutators, which at the transmitting station ensure the radiation of a regular and uniform succession of trains of waves, and at the receiving station ensure the connection of the receiver with the antenna during, and only during, the passage of each train 85 of waves, the regulator of the receiving station being synchronized with that of the transmitting station.

Agreement of phase of the second and receiving apparatus is easily obtained, at 90 the receiving station, by regulating the relative position of the fixed contact and of the axis of the commutator.

The frequency of interruption of the commutator may be equal to, or a multiple 95 or sub-multiple of the frequency of the trains of waves, more particularly in the case of radiations in which use is made of alternating current to charge the condenser, and of the attenuation of the spark by resonance with the low frequency circuit.

For example if the frequency of the alternator at the sending station is 1000 and this is also the frequency of interruption of the commutator at the receiving station, the apparatus at the latter station will operate 105 effectively whatever be the musical frequency of the spark produced at the sending

station; whether 2000 (one spark per half wave of alternator E. M. F.), or 1000 (one spark for each complete alternation), or 666 (one spark in three half waves of E. M. F.) or 500, etc., according to the degree of attenuation of the spark.

There may in some cases (for instance with a note of 2000 or of 666 frequency) be a change in the musical note, which in the former case will be converted into a note of 1000 frequency and in the second case into one of frequency 333.

The commutator may be placed elsewhere than in the antenna circuit, for instance in the secondary circuit of the receiver, or in the telephone circuit, or in any other circuit provided that it fulfils the condition above set out, viz to remove the telephone or recording apparatus from the influence of antenna between each two trains of waves.

If a receiving station commonly receives messages at two or three different frequencies a similar number of commutators may be employed connected in parallel and rotating at speeds corresponding to these different frequencies.

The commutator may be made in any desired fashion so long as it fulfils the conditions above set out concerning the regulation of the frequency, of the phase and of the time of interruption.

Take for instance a rotary commutator or a vibratory interrupter.

In the accompanying drawings, Fig. 1 shows diagrammatically the application of this system to a transmitting station; while Figs. 2 and 3 show its application to the receiving station.

A is the transmitting antenna, joined to earth at T through the spark gap O supplied by the induction coil I.

The primary circuit of the coil, supplied by the source P is regularly interrupted by the aid of the toothed wheel B on which the contact D bears. There is insulation between the teeth.

The wheel being rotated at a uniform speed, controlled by a special regulator, the frequency of the sparks, and in consequence, of the trains of waves, will be equal to the product of the speed and the number of teeth, say f_1 .

A key M allows Morse signals to be sent. For a greater simplicity, the accessories, relays and so on adapted to ensure good electrical and mechanical operation are not shown on the drawings.

The apparatus for regulating the speed can be of any suitable kind,—mechanical, clockwork, electrical, or the like. It can be rotary, vibratory, oscillatory, and can be combined either directly or indirectly with the wheel B. This wheel can equally be replaced by a vibratory or oscillatory system.

The commutator B or similar apparatus can work in various ways, at the transmitting station, to regulate the frequency of the trains of waves. Fig. 1 shows only one particular instance.

It can operate directly on generators, to produce an alternating current, of which it regulates the frequency, or again it can be employed as a tickler at the bottom of the antenna, especially in the case when continuous waves are used.

Figures 2 and 3 relate to the receiving station. A' indicates the receiving antenna, R' a receiver, T' earth. The commutator wheel B', equivalent to the wheel B of the transmitting station can be connected in this circuit.

This wheel rotates at a speed and carries a number of teeth or segments such that the frequency of the interruptions is equal to that of the trains of waves, controlled by B at the transmitting station.

Further, the contact D' is for the purpose of the present invention fixed on another wheel E' concentric with B' and insulated from it electrically. By moving this contact by an amount at most equal to the pitch of the wheel B' it will always be possible to secure agreement of phase between the wave trains and the successive contacts of D' with the teeth of B'.

It is obvious that the speed regulating apparatus of the wheel B' can be made similar to that at the sending station or of other appropriate type.

Further, the commutator wheel B' can be inserted in any other circuit of the receiving station besides the antenna circuit, for example either in the secondary circuit or in the telephone circuit, etc., provided that it fulfils the condition stated above, viz to withdraw the telephone or receiving apparatus from the influence of the antenna between two trains of waves.

Now suppose absolute synchronism between the trains of waves and the interruptions of the commutator at the receiving station is not attained or has been destroyed, that is to say the case in which $f_2 \geq f_1$; where f_2 is the frequency of the commutator at the receiving station and f_1 the frequency of the trains of waves transmitted. This can be remedied at the receiving station by continuously regulating the relative position of the wheel E' and the wheel B'.

In other words, if n_2 is the number of segments or teeth of the wheel B', and v_2 its angular speed, $f_2 = n_2 v_2$.

If $f_2 \geq f_1$, it will suffice to impress upon the wheel E' an angular speed equal to

$$V = \pm \left(\frac{f_2 - f_1}{n_2} \right) = \pm \left(V_2 - \frac{f_1}{n_2} \right)$$

revolutions per second.

This angular speed is determined experi-

mentally by leaving the wheel E^1 stationary and noting the periodic time T of the interferences between the trains of waves and the interruptions of the commutator B^1 .

5 We have further

$$T = \frac{1}{f_2 - f_1} \text{ seconds.}$$

10 Whence

$$V = \pm \left(\frac{1}{Tn_2} \right)$$

Practically, the periodic time T of the 15 interferences is determined very easily; if the wheel E^1 is stationary, the signals being received intermittently, it is sufficient to notice the time between two successive reappearances of the signals.

When synchronism is perfect, the signals 20 are received continuously or more usually, the silence is permanent; in this latter case it is then sufficient to regulate once for all the position of the contact D^1 which regulates the phase to obtain a continuous 25 reception.

When the difference $f_2 - f_1$ is exceedingly small, the periodic time T becomes considerable and the speed V to be impressed upon the wheel E very low.

30 It is then sufficient to correct from time to time the position of the contact D by hand.

If the difference $f_2 - f_1$ is appreciable, the 35 rotation of the wheel E^1 can be obtained mechanically and its regulation to the speed V brought about by any effective means.

In order to avoid static charge on the 40 receiving antenna between the passage of two trains of waves, which would produce a parasitic oscillation on connection to the receiver, a second contact like D^1 can be provided, which puts the wheel B^1 directly to earth between the successive passages of 45 the teeth of this wheel under the contact D^1 .

Having now particularly described and ascertained the nature of my said invention and in what manner the same is to be performed, I declare that what I claim is: 50 1. A wireless telegraphy system comprising a transmitting station with a regulator to ensure a regular and uniform succession of trains of waves and a receiving station with a regulator to cause the receiver to 55 come into operation only during the time of transmission of such trains.

2. A wireless telegraphy system compris-

ing a transmitting station with a regulator to ensure a regular and uniform succession 60 of trains of waves and a receiving station with a commutator arranged to put the antenna into and out of operative relation with the receiver at a frequency equal to a multiple of that of the trains of waves to be received.

65 3. A wireless receiving station with a commutator arranged to put the antenna into and out of operative relation with the receiver at a frequency equal to a multiple of that of the trains of waves to be received, and means to regulate the speed of the commutator.

70 4. A wireless receiving station comprising an antenna, a receiver, a commutator arranged to put the antenna and receiver into and out of operative relation with a frequency fixed with respect to that of the trains of waves to be received, and means to ensure coincidence between successive 75 connections of the receiver with the antenna and the beginning of successive receiving trains of waves.

75 5. A wireless receiving station comprising an antenna, a receiver, a commutator arranged to put the antenna and receiver into and out of operative relation with a frequency fixed with respect to that of the trains of waves to be received, and means to regulate the time of make and break of the connections of the receiver to the antenna.

80 6. Wireless telegraphy receiving apparatus including a commutator for periodical closing, and indicating means so arranged that the indicating means is influenced solely at the exact moment of the 85 passage of receiving waves, synchronizing means, and means to ensure concordance of phase between the regular succession of continuous waves and the regular succession 90 of closing by the commutator.

95 7. In wireless telegraphy, an antenna connected to earth, a receiver and a commutator in the antenna circuit arranged to connect and disconnect the receiver from the 100 antenna circuit with a frequency equal to that of the trains of waves, and means to vary the time of operation of the commutator.

105 In testimony whereof I affix my signature.
